(57) **CLAIM**

The ornamental design for an oscillating fan with decorative grill as shown and described.

DESCRIPTION

FIG. 1 is a front elevational view of the oscillating fan with decorative grill of the present invention;

FIG. 2 is a rear elevational view of the oscillating fan with decorative grill of FIG. 1;

FIG. 3 is a left side elevational view of the oscillating fan with decorative grill of FIG. 1;

FIG. 4 is a right side elevational view of the oscillating fan with decorative grill of FIG. 1;

FIG. 5 is a top plan view of the oscillating fan with decorative grill of FIG. 1; and,

FIG. 6 is a bottom plan view of the oscillating fan with decorative grill of FIG. 1. The broken line showing of “Team Logo” in FIGS. 1,3,4 and 5 is your illustrative purposes only and forms no part of the claimed design.
